CLAIM

The ornamental design for a case for electronic communications device, as shown and described.

DESCRIPTION

FIG. 1 is a front perspective view of a case for electronic communications device, showing my new design;

FIG. 2 is a rear perspective view thereof, with the support leg shown in a retracted position;

FIG. 3 is a second rear perspective view thereof, with the support leg shown in an extended position;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and

FIG. 9 is a bottom plan view thereof;

FIG. 10 is a front perspective view of the inner shell component of the case, shown isolated for clarity of disclosure;

FIG. 11 is a rear perspective view of the inner shell component of the case, shown isolated for clarity of disclosure; FIG. 12 is a front perspective view of the outer frame component of the case, shown isolated for clarity of disclosure;

FIG. 13 is a rear perspective view of the outer frame component of the case, shown isolated for clarity of disclosure;

FIG. 14 is a front perspective view of the support leg component of the case, shown isolated for clarity of disclosure;

FIG. 15 is a rear perspective view of the support leg component of the case, shown isolated for clarity of disclosure;

FIG. 16 is an exploded front perspective view of the components of the case, which are shown separated for clarity of disclosure; and,

FIG. 17 is an exploded rear perspective view of the components of the case, which are shown separated for clarity of disclosure.

The case for electronic communications device, in which the claimed design is embodied, consists of an outer frame component, an inner shell component, and a support leg component. However, the claim is directed to the overall ornamental appearance of the case for electronic communica-

cations device in its entirety and does not extend to the ornamental appearance of each of the individual components.

The broken lines and regions bounded by broken lines depict portions of the case for electronic communications device that form no part of the claimed design. The interior of the inner shell of the case shown in FIGS. **1, 4, 10** and **16** forms no part of the claimed design.
